UNITED STATES PATENT OFFICE.

CHARLES LONGENECKER, OF SPRINGFIELD, MASSACHUSETTS, ASSIGNOR TO QUIGLEY FURNACE AND FOUNDRY COMPANY, A CORPORATION OF MASSACHUSETTS.

APPARATUS FOR FEEDING FINELY-DIVIDED FUEL.

1,191,203.

Specification of Letters Patent. Patented July 18, 1916.

Application filed September 22, 1913. Serial No. 791,173.

To all whom it may concern:—

Be it known that I, CHARLES LONGENECKER, a citizen of the United States of America, residing at Springfield, county of 5 Hampden, State of Massachusetts, have invented certain new and useful Improvements in Apparatus for Feeding Finely-Divided Fuel, of which the following is a specification.

10 My invention relates to apparatus for feeding finely divided fuel to the combustion chambers of furnaces, and is designed to simplify the apparatus heretofore employed and heighten the efficiency thereof.

15 Heretofore it has been customary to handle the supply of such pulverized fuel by various mechanical conveyers, such as screw conveyers, and to force the desired quantity of fuel into the combustion chamber by

20 the action of currents of compressed air acting upon falling streams of the fuel and driving the particles before it into the interior of the combustion chamber. Apparatus of the above described type requires the

25 use of considerable machinery subject to disarrangement and clogging, absorbs power in the operation of such machinery and is open to the practical objection that the back pressure of the compressed air operating in

30 confined spaces connected to the bottom of the hoppers containing the supply of pulverized fuel is continually tending to force air currents up through the body of fuel in said hoppers and break the seal and interfere with the operation of the apparatus

35 as a whole. I have overcome these difficulties and greatly reduced the initial cost of the apparatus required by the invention hereinafter more particularly described, in

40 which I employ the suction action of an air injector apparatus to lift or draw the pulverized fuel from the hopper or other receptacle, and then by continuation of the same operation force the fuel so drawn out

45 through the discharge orifice of the injector apparatus to the fuel burner and combustion chamber.

The best form of apparatus at present known to me embodying my invention is 50 illustrated in the accompanying sheet of drawings in which,

Figure 1 is a side view with parts broken away showing my apparatus and a portion

of the wall of a combustion chamber (not shown), and Fig. 2 is a detail plan view of 55 the burner and its connections.

Throughout the drawings like reference characters indicate like parts.

1 represents a portion of the wall of a combustion chamber perforated to receive 60 the burner tube 2, in which is centered the fuel supply nozzle 3. This nozzle is preferably connected to fuel supply pipe 5, which enters the tube 2, at one side and is connected to the nozzle 3, by an ordinary form 65 of T 4, the rear end of which is plugged in any suitable manner.

6, is a receptacle for finely divided fuel such as pulverized coal, which preferably has one or more sides inclined to the horizontal plane, as shown at 12.

7, is a hollow casting forming the chamber of an ordinary fluid injector in which the operative jet of fluid under pressure, such as compressed air, is supplied through 75 the nozzle 8. The pipe 5, is connected to the discharge outlet of this injector. The suction inlet of the injector is connected by pipe 11 to the interior of the hopper 6, such pipe 11, preferably extending to a point 80 near the bottom of said hopper, such bottom being of relatively small area with reference to the other dimensions of the hopper.

9 is a pipe controlled by valve 10, which 85 supplies compressed air from any suitable source to the injector nozzle 8.

In operation the hopper 6, is kept suitably replenished with pulverized fuel, compressed air is supplied through pipe 9, at 90 a pressure of about 20 pounds or more. Auxiliary air of combustion is also supplied to the burner tube 2, at a considerably lower pressure, sufficient to produce the necessary flow of air to support combustion. The 95 partial vacuum produced at the suction inlet of the injector 7, in accordance with the well known principle of the injector, sucks up through the pipe 11, the necessary quantity of pulverized fuel drawn from the 100 bottom of the hopper 6. The fuel mixed with air so drawn into the injector 7, is driven out by the propulsive force of the jet from nozzle 8, through the discharge outlet of the injector and the pipe 5, 105 to nozzle 3. At that point, it is discharged

into the burner tube 2, intimately mingled with the additional air passing therethrough in quantity sufficient to produce complete combustion, and the said combustible mixture is then driven into the combustion chamber of the furnace (not shown). By regulating the flow of compressed air through the injector by means of the valve 10, or equivalent controlling device, the amount of fuel drawn from the hopper and delivered to the combustion chamber is automatically regulated.

The advantages of my invention comprise the fact that all moving and wearing parts are dispensed with, the regulation is absolutely automatic without requiring any delicate apparatus whatever, the consumption of power is limited to the creation of the necessary air blast, and no back pressure whatever is created in the hopper. In consequence of the last fact, the supply of coal in the hopper may be permitted to drop to the extreme end of the suction pipe 11, without any breaking of the seal in the hopper, or interference with the even action of the apparatus.

Another important advantage results from overcoming the difficulty heretofore encountered in controlling the movement of pulverized fuel in the ordinary form of hopper. Such fuel tends to pack or bank up in curious and uncertain ways, which have made it extremely difficult to secure the constant and efficient feeding action of the ordinary screw conveyer or other mechanical feeding device. With my invention the suction action tends to positively draw down all fuel in the hopper to the point of outlet, *i. e.*, the end of the suction tube, and by properly inclining one or more sides of the hopper, as shown at 12, in accordance with the best obtainable practice, and placing the inlet to the suction pipe at the narrower bottom of the hopper, all cak-

ing or banking or chimneying in the body 45 of fuel in said hopper is avoided.

Various changes could be made in the details and relative arrangement of parts of the apparatus illustrated and described herein without departing from the principle 50 of my invention, so long as the manner of operation above described is retained.

Other forms of burners, injectors, hoppers, and connecting pipes might be substituted for those illustrated, to suit varying 55 conditions of operation, but all such I should consider within the scope of my invention so long as the injector principle is employed by which the same current of air operates to draw the fuel from the bottom of a suitable receptacle by suction and carry the said fuel entrained in the air current to the combustion chamber for mixture with the auxiliary air necessary to produce complete combustion at that point. 60

Having, therefore, described my invention, I claim:

In a system for conveying and burning pulverized fuel, the combination, with a furnace having a feed-hole, of a pulverized 70 fuel reservoir having a normally closed bottom and open top, of an air-ejector located above the top of the said fuel and supplied with fluid under pressure and having its suction-pipe extended through the 75 fuel near to the bottom of the reservoir to lift the fuel therefrom, a feed-nozzle connected with the feed-hole of the furnace and with an air-supply-pipe, and the delivery 80 pipe of the ejector being extended within the feed-nozzle near the feed-hole, and operating in connection with the feed-nozzle to drive the fuel into the combustion-chamber of the furnace.

CHARLES LONGENECKER.
